UNITED STATES PATENT OFFICE.

HENRY TIELKEMEYER, OF ST. LOUIS, MISSOURI.

CURTAIN AND DRAPE FIXTURE.

Application filed April 22, 1926. Serial No. 103,771.

This invention relates to improved curtain and drape fixtures.

An object of the invention is to provide an improved curtain and drape fixture including a pair of brackets for supporting an upper rod having means whereby the rod may be connected with the brackets and prevented from becoming disconnected, and a pair of lower brackets for a lower rod provided with means for connection with the lower rod whereby the lower rod may be supported in different positions with respect to the upper rod as may be required by variations in the length of drapes connected to both the upper and lower rods.

Other objects will appear from the following description, reference being made to the accompanying drawing in which

Fig. 1 is a plan view of the brackets having the upper rod in connection therewith.

Fig. 2 is a front elevation of the complete invention comprising the upper and lower fixtures.

Fig. 3 is a view partly in section showing the connection of one end of a rod to one of the upper fixtures.

Fig. 4 is an inner side elevation of the right hand bracket for the lower rod.

Fig. 5 is an inner side elevation of the left bracket for the lower rod.

Fig. 6 is a plan view of one of the lower brackets.

Each bracket included in the upper fixture comprises a body 1 arranged to be attached to a window frame or to a door and having rigid connection with an angular arm 2 extending upwardly therefrom. The ends 3 of the respective arms 2 extend toward each other and, when the fixture is properly applied, are in alinement. The extremity of each end portion 3 is provided with a vertical slot 4 extended in the upper side of each arm to form a socket 5. Each end of the rod 6 is provided with a rigid projection 7 arranged to pass into the corresponding slot 4 and with a knob 8 on the end of the projection 7 arranged to seat in the corresponding socket 5. The knobs 8 are of greater diameter than the width of the slot 4 so that the rod composed of the telescoping sections, as shown, will be firmly held in connection with the brackets.

Each of the end portions 3 of the supporting arms of the brackets is formed with a circumferential groove 9, and a sleeve 10 encircles the end of each bracket arm and

is pressed into the groove 9, thus obtaining a connection in which the sleeve 10 is rotatable on the bracket arm but cannot be detached therefrom. Each sleeve 10 is formed with a slot 11 extending from its outer end to a depth equal to the combined length of the slot 4 and the socket 5. Thus, when the sleeves 10 are turned to register the slots 11 with the slots 4 and sockets 5, the curtain rod may be applied in the obvious manner, after which the sleeves 10 may be turned to place the slots 11 out of registration with the slots 4 and sockets 5, as shown in Fig. 2. This will prevent accidental detachment or disconnection of the rod 6 from the brackets, but will permit easy disconnection of the parts when desired.

The lower rod 12 is of similar construction, being provided on each end with a projection 13 and a knob 14 corresponding to the projections 7 and knobs 8.

Two brackets are provided for the lower rod, each comprising a piece of sheet metal folded to provide a base 15, an outwardly extended part 16 and an inwardly extended part 17 having integral connection 18 with the outer edge of the part 16. The parts 16 and 17 are approximately parallel and are spaced sufficiently to receive the knobs 14 between them so as to obtain an ornamental effect. The part 16 of each bracket is provided with a series of vertically alined holes 19 from each of which a slot 20 extends downwardly and inwardly, and thence upwardly to form a seat 21. Each seat 21 is clearly defined from the connecting slot 20 by an abrupt shoulder 22. The holes 19 are of sufficient diameter to permit the knobs 14 to pass therethrough. The slots 20 and seats 21 are of narrower width than the diameter of the holes 19 so that the knobs 14 cannot pass through them; but are of sufficient width to permit the projections 13 to pass through the slots 20 and become seated in the seats 21, as shown. Thus the rod 12, provided with the projections 13 and knobs 14, may be conveniently applied in any required position on the brackets in conformity with the length of the drape to be connected therewith.

It is a familiar experience that drapes often shrink as a result of use or cleaning and require alteration, or change of position of the brackets and the lower rod before they can be used again. The present invention obviates this trouble and provides for

accurate and convenient adjustment of the rod in conformity with the variation of the length of the drape.

- I am aware that the specific structure and arrangement of the parts may be varied without departure from the nature and principle of the invention. I do not restrict myself unessentially, but what I claim and desire to secure by Letters Patent is:—
- 10 1. A drape or curtain fixture comprising a bracket having a vertical series of holes and a slot extending from each hole downwardly toward the inner edge of the bracket and having an upwardly extending seat de-

fined from the upper edge of the connected slot by an abrupt shoulder and arranged to receive a projection from the end of a curtain rod.

2. A drape or curtain fixture comprising a bracket having a hole near one edge and a slot extending from said hole downwardly and toward the inner edge of the bracket and having an upwardly extending seat defined from the upper edge of the connected slot by an abrupt shoulder and arranged to receive a projection from the end of a curtain rod.

HENRY TIELKEMEYER.
